PUMPING APPARATUS

Victor J. Mill, Lawrence, Mass., assignor to Lawrence Machine and Pump Corporation, Lawrence, Mass., a corporation of Massachusetts

Application April 12, 1945, Serial No. 587,906

1 Claim. (Cl. 103—103)

1

This invention relates to a pumping apparatus and more particularly to an apparatus of this character in which the pump is submerged in a liquid containing abrasive materials in suspension or liquids which are of a corrosive mixture.

One of the principal uses of this pump is for pumping slurry which may consist of a watery mixture of powdered raw materials for hydraulic cement.

One of the objects of this invention is to so organize the pump that the side pressure exerted by the movable elements against the liquid which is being pumped is balanced relative to the center of rotation of the movable elements and thereby avoid side thrust on the shaft which supports the movable pump element and the bearings in which this shaft is journaled.

Another object of this invention is to so mount the shaft of the pump on the cover of the tank containing the liquid material which is being pumped, that an effective seal is produced between the pump shaft and the top of the tank which will prevent the escape of any gases from the tank during the operation of the pump.

A further object of this invention is to provide means which will positively permit of efficiently journaling the impeller of the rotary pump on the top of the tank and still prevent the escape of any gases which may be generated in the tank upon agitating liquids of a corrosive character.

In the accompanying drawings:

Fig. 1 is a vertical section of a pumping apparatus embodying my invention and showing one form of means for preventing the escape of gas from the interior of the tank.

Fig. 2 is a horizontal section, on an enlarged scale, taken on line 2—2, Fig. 1.

Fig. 3 is a fragmentary sectional view, similar to Fig. 1, but showing an alternate form of the means for sealing the joint between the top of the tank and the impeller shaft for the purpose of preventing the escape of gases from the tank.

In the following description, similar characters of reference indicate like parts in the several figures of the drawings:

Although the tank which holds the liquid containing an abrasive in solution or the liquid which contains corrosive ingredients may be variously constructed, this tank may comprise a bottom 10, an upright side wall 11 and a top or cover 12 which is detachably connected at its outer edge with a flange 13 on the upper end of the tank body by means of bolts 14 or the like.

Within the lower part of this tank and submerged in the liquid therein is located the casing of a centrifugal pump which comprises an

2

upper head 15 provided with a downwardly projecting peripheral wall 16 and a lower head 17 which is detachably connected at its edge with the lower edge of the peripheral wall by means of screws 18 or the like, thereby forming a circular pressure chamber between these members of the casing.

On its upper side the upper head of the pump casing is provided centrally with a tubular upwardly projecting neck 19 which is arranged concentrically with the axis of the casing.

The pump casing is suspended within the tank from the cover of the same by means of an upright tubular housing 20 which is provided at its lower ends with an external flange 21 which is detachably connected by means of screws or bolts 22 with a flange 23 at the upper end of the casing neck 19 and this housing is detachably connected at its upper end with the underside of 20 the tank cover by means of bolts or screws 24 connecting an external flange 25 at the upper end of this housing with said tank cover.

The liquid to be propelled or lifted from the tank is admitted to the pump casing through an 25 inlet opening 26 arranged centrally on the lower head of the pump casing, this inlet opening being surrounded by means of a downwardly flaring flange 27 which terminates close to the bottom of the tank so as to permit of vertically 30 removing the entire contents of the tank by means of this pump.

On diametrically opposite sides of the peripheral wall of the pump casing the same is provided with a pair of outlet openings 28, 28 through 35 which the liquid drawn into the casing through the central opening in the bottom thereof, is discharged from the pump casing. The peripheral wall of the pump casing is so constructed that the same forms two volutes 29, 29, each of which is 40 arranged circumferentially of the casing and has its rear end 30 arranged adjacent to the inner side of one of the outlet openings 28 and relatively close to the axis of the casing while its front end 31 is arranged on the outer side of the other outlet opening 28 and farther from the axis, as shown 45 in Fig. 2.

The liquid discharged through these two outlets of the pump casing is carried to the exterior of the tank by means of two upright delivery conduits, each of which comprises a lower vertical tubular section 32 which extends upwardly from one of the outlet openings 28 of the pump casing, an intermediate tubular section 33 arranged within the tank and having its lower end connected 50 with the upper end of the lower section 32 by means of bolts 34 passing through external flanges

35, 36 arranged on the respective ends of these conduit sections. The upper end of the intermediate conduit section engages with the underside of the tank cover and communicates with an opening 37 therein. Above the tank cover is arranged the upper section 38 of the respective delivery conduit from which the liquid removed from the tank is delivered to the place where the same is required. This upper section of the intermediate delivery conduit section 38 engages with the upper side of the tank cover and communicates with the opening 37 therein. The intermediate and upper sections 33, 38 of each liquid delivery conduit are secured to the lower and upper sides of the tank cover by means of bolts 39 passing through the tank cover and flanges 40, 41 arranged on the adjacent parts of the intermediate and upper conduit sections, as shown in Fig. 1.

For the purpose of producing a rigid structure and maintaining the parts in their proper relative position the upper end of the central neck 19 of the pumping casing is connected by means of webs or arms 42 with the upper ends of the lower conduit sections 32, as shown in Fig. 1.

Within the pump casing is arranged the rotary impeller whereby the liquid to be pumped is drawn into the casing through the inlet in the lower head thereof and then thrown radially outward therein by centrifugal force and discharged from the casing through the outlet openings in the peripheral wall thereof. Although this impeller may be variously constructed, the same preferably comprises a lower disk 43 provided centrally around its axis with a liquid inlet opening 44, an upper disk 45 provided centrally with an upwardly projecting hub 46 which is arranged in the lower part of the upper neck 19 of the casing, and a plurality of curved vanes or blades 47 arranged in an annular row in the space between the lower and upper disks of the impeller and connected therewith. Upon rotating the impeller in the direction in which they present their convex surfaces foremost and in the direction in which the volutes of the casing gradually widen radially from the axis of the casing and impeller, as indicated by the arrow in Fig. 2, the liquid is drawn from the lower part of the tank upwardly into the central inlet of the pump casing, then forced radially outward in the casing and discharged through the outlet openings 28 in the peripheral wall of the casing and then forced upwardly through the delivery conduits and discharged above the top of the tank.

Rotation of the impeller for this purpose is accomplished by means which include an upright impeller driving shaft 48 which has its lower part arranged in the housing 20 and the neck 19 of the casing and has its lower end connected with the hub of the impeller. This connection between the impeller and the driving shaft may be effected in any suitable manner but preferably by securing the hub of the impeller between a downwardly facing shoulder 49 on this shaft engaging with the lower end of the impeller hub by a screw nut 50 applied to the lower end of the impeller shaft. The impeller is compelled to turn with the impeller shaft by means of a longitudinal key 51 interposed between these parts.

The impeller shaft has its upper part projecting above the top of the tank cover and is journaled so that it can rotate about a vertical axis but is incapable of moving vertically, this being accomplished by means of upper and lower bear-

ings 52, 53 which receive the upper part of this shaft and rotatably support the same at one point immediately above the cover of the tank and at another point more remote from the cover. These bearings are preferably so constructed that they not only provide lateral support for the impeller shaft and the impeller carried thereby, but also support the impeller shaft and impeller against downward thrust. Various means may be provided for supporting the stationary members of the lower and upper bearings, such for example, as a standard 54 which surrounds the upper part of the impeller shaft and is secured at its lower end to the cover of the tank.

Power for driving the impeller shaft and impeller may be derived from any suitable source, such as an electric motor or the like, the shaft of which may be connected by suitable driving means or gearing with an intermediate shaft 55 having its lower end connected with the upper end of the impeller shaft by means of a coupling similar to that shown at 56 in Fig. 1.

When the parts of this pumping apparatus are in their operative position ready for use, only the upper parts of the impeller shaft 48 are engaged by the bearings 52, 53 and that part of the impeller shaft below the cover of the tank and the impeller mounted on the lower end of this shaft are suspended freely and rotate without contacting any part of the housing or any part of the pump casing and it therefore is unnecessary to service any bearings for this shaft below the level of the liquid in the tank.

Owing to the peripheral wall of the casing of the pump being provided with outlet openings on diametrically opposite sides of the axis of the casing and the impeller and its shaft, the radial outward thrust which is exerted by the impeller on the liquid which is being pumped while being discharged through these outlet openings is equalized due to the counterbalancing effect of the impeller blades on the streams of liquid which are discharged through these two outlet openings. As a result the radial pressure of the impeller blades against these two streams of liquid is uniform and the impeller shaft is maintained in its central axial position without requiring bearings of any kind for supporting the same at or near its lower end, thereby avoiding the necessity of dismantling the pumping apparatus in order to gain access to such bearings as has been the case heretofore.

When pumping liquids which give off a gas that should be retained in the tank, for example, when pumping liquids containing a corrosive element, means are provided whereby a tight fit is produced between the cover of the tank and the impeller shaft so as to permit the latter to rotate freely and still prevent the escape of objectionable gases.

Various means may be provided for sealing the joint between the impeller shaft and the tank cover. As shown in Fig. 1, this is accomplished by providing the cover of the tank with an annular cup 57 which is adapted to hold a sealing liquid such as water or oil and which is mounted on the tank cover around the adjacent part of the impeller shaft and having an open top, a tubular skirt 58 having its upper part secured to the impeller shaft and its lower part dipping into the sealing liquid in the sealing cup, and an annular lid 59 surrounding the tubular skirt and secured to the upper end of the sealing cup 57, as shown in Fig. 1.

Instead of employing a liquid seal between the

cover of the liquid tank and the impeller shaft, the same results can be obtained by means of the stuffing-box, which is shown in Fig. 3, and which comprises a cup-shaped holder 60 arranged within the upper part of the housing 20 and surrounding the adjacent part of the impeller shaft and secured to the tank cover, a tubular gland 61 arranged within the upper part of the stuffing cup and around the adjacent part of the impeller shaft and adapted to be drawn downwardly by means of adjusting screws 62 connecting the same with the stuffing cup, and an annular packing 63 interposed between the bottom of the stuffing cup and the lower end of the stuffing gland and surrounding the adjacent part of the impeller shaft. Upon tightening the screws 62, the packing 63 will be pressed tightly against the periphery of the impeller shaft and thus form a seal between the same which will prevent the escape of gas from the tank and still permit the impeller shaft to rotate freely.

As a whole this pumping apparatus is very simple in construction and low in cost, the same is very efficient in operation and due to the uniformity of the radial pressure exerted by the impeller against the liquid being pumped, it is possible to maintain this apparatus in good working condition with minimum servicing and cost of maintenance.

I claim as my invention:

Apparatus for pumping abrasive or corrosive liquids from a tank having an enclosing cover, comprising a centrifugal pump casing arranged in said tank near the bottom thereof with its axis vertically disposed, said pump casing having a horizontally disposed circular working chamber communicating with a downwardly directed central inlet and communicating with two opposite, horizontally enlarging volutes leading to diametrically opposite outlets in the upper wall of said pump casing at the enlarged ends of said volutes, and said casing also having an upwardly projecting tubular cylindrical neck communicating

with said working chamber, a circular, bladed centrifugal impeller arranged in said pump casing to rotate coaxially therein and having a cylindrical hub arranged in said neck, the maximum diameters of said impeller and hub being substantially less than the internal diameters of said working chamber and neck, respectively, whereby said impeller is free to move horizontally in said pump casing and is centered only by the balanced liquid pressures provided by said opposite volutes and outlets, a drive shaft secured coaxially to said hub and extending upwardly through said cover, an upright tubular housing surrounding said drive shaft in spaced relation thereto and secured at its lower end to said neck and at its upper end to the under side of said cover, outlet pipes each secured at its lower end to the top wall of said pump casing around a corresponding one of said outlets and at its upper end to the under side of said cover around an outlet opening therein, and said neck being formed to provide a pair of integral radial arms and secured at its outer end to a corresponding one of said outlet pipes.

VICTOR J. MILL.
